INSTRUMENT FOR SUTURING

John D. Karle, Roselle Park, N. J., assignor to The Singer Manufacturing Company, Elizabeth, N. J., a corporation of New Jersey

Application December 12, 1940, Serial No. 369,692

38 Claims. (Cl. 112—169)

This invention relates to thread-suturing of flesh wounds resulting either from accidental or surgical causes and it has for a primary object to provide a new and improved method of suturing and a simple and practical instrument for carrying out that method.

Several methods of suturing wounds are known in the art of surgery. Among these, one which has been commonly employed consists in passing through the flesh, at opposite sides of the wound, a curved needle having, in the butt end thereof, an eye carrying a suitable suture-thread. After the needle has been passed through the flesh that end of the suture which projects from the flesh at the side of the wound at which the needle enters is tied with the portion projecting from the flesh at the opposite side of the wound, thereby completing the stitch, after which the suture is severed between the wound and the needle.

That method, which requires a considerable amount of skill, has been both slow and tedious but has been used almost universally for the want of a better method and means with which to practice the same.

This invention has as an object to provide a method of suturing wounds which to practice will not require a great amount of skill; which will be materially faster than that heretofore used; which will be less tedious; which will obviate the necessity of hand manipulation of the suture-thread to lock the stitches; in which the various stitches will be connected together; and in which the suture extending from one stitch to the next will overlie the wound and assist in holding the opposite marginal portions thereof in alignment and in contact with each other.

One phase of the present improved method comprises the suturing of wounds by means of two threads, one of which is first passed inwardly and thence outwardly through the flesh at opposite sides of the wound and the other of which is interlocked with the first to form a locked stitch. By repeating this operation at spaced intervals along the wound, with the threads extending from one stitch to the next, the wound will be closed by a two thread lock-stitch seam.

The beginning end of the seam may be prevented from loosening or ravelling by the tying together of the two threads before the making of the first stitch. The improved lock-stitch method of suturing wounds also provides for the securing of the finishing end of the seam against loosening or ravelling by making two stitches through the same or closely adjacent punctures, thereby form-

ing a tying stitch, and severing the threads at a substantial distance from the last stitch.

In one utilization of the proposed method of suturing, the two threads are additionally locked together at the center at the outer face of the wound and overlie the same thereby to give added strength to the seam and better to hold the opposite marginal portions of the wound aligned and in contact with each other.

10 The means provided for practicing the above described lock-stitch method comprises a hand-carried and hand-manipulated instrument which, in its preferred form, includes a support having a handle, a spool of suture-thread carried by said support, a curved eye-pointed suture-carrying needle carried by the support and adapted to have the eyed end thereof passed into and out of the flesh at opposite sides of the wound, and a shuttle mechanism including a suture-carrying 15 bobbin, also carried by the support and adapted to cooperate with the needle-suture in the formation of lock-stitches.

20 Drawings depicting the improved method of suturing wounds and means for practicing that method have been annexed as a part of this disclosure and in said drawings,

25 Figs. 1, 2, 3, 4 and 5 are perspective views of my improved lock-stitch surgical stitching instrument illustrating its various stages of use 30 when practicing the method of suturing wounds in accordance with the present invention.

Fig. 6 is a plan view of the instrument shown in Figs. 1 to 5.

Fig. 7 is a plan view of a portion of the needle 35 and shuttle supporting shaft showing particularly a shuttle-controlling cam-groove therein.

Fig. 8 is a needle-end elevation of the instrument showing, in full and dotted lines, different 40 positions of the shuttle mechanism relative to the cooperating needle.

Fig. 9 is a transverse section on the line 9—9 of Fig. 6, showing a shuttle-controlling cam-groove and its cooperating follower.

Fig. 10 is a transverse section in the line 10—10 45 of Fig. 6, illustrating a detent mechanism for retaining the shuttle mechanism in an out-of-the-way position relative to the needle.

Fig. 11 is a vertical section on the line 11—11 50 of Fig. 6, showing locking means for the spool carrying a supply of needle-suture.

Fig. 12 is a disassembled perspective view of the principal elements of the supporting and locking means for the needle-suture spool.

Fig. 13 is a horizontal section on the line 13—13 55 of Fig. 8, showing needle-clamping means.

Fig. 14 is a transverse section on the line 14—14 of Fig. 6, showing means for supporting the shuttle mechanism on its shaft.

Fig. 15 is an enlarged side elevation, partly in section, of the shuttle mechanism.

Fig. 16 is an enlarged longitudinal vertical section on the line 16—16 of Fig. 6.

Fig. 17 is an enlarged horizontal sectional view of a portion of the shuttle mechanism showing, more particularly, means for holding the shuttle against rotary and endwise movement in its holder and for locking the bobbin against rotation in the shuttle.

Fig. 18 is a disassembled perspective view of the shuttle-holder, the shuttle and the bobbin.

Figs. 19 and 20 are views illustrating one improved suturing seam which may be made by the improved suturing instrument.

Fig. 20^a is a view illustrating one form of tying stitch for tying-off the finishing end of a suturing seam.

Fig. 21 is a view illustrating another improved suturing seam which may be produced by the instrument and another form of tying stitch for tying off the finishing end of a suturing seam.

Fig. 22 is an enlarged transverse section on the line 22—22 of Fig. 21 illustrating the securing action of a tying stitch made at the completion of a suturing seam.

Figs. 23 and 24 are perspective views of the front end portion of the improved instrument illustrating the manner in which it is manipulated in making the seam illustrated in Fig. 21.

Fig. 25 is a perspective view of a modified form of suturing instrument adapted for forming individual suturing stitches and also for forming a plurality of connected suturing stitches in the nature of a chain-stitch seam.

Figs. 26, 27 and 28 are views illustrating various forms of suturing operations adapted to be performed with the instrument illustrated in Fig. 25.

While this surgical stitching instrument, illustrated in Figs. 1 to 18 inclusive, has been developed primarily to practice the improved lock-stitch method of suturing wounds, as hereinbefore described, it is believed that the method and the operation of the instrument in performing the same can best be understood after having first obtained an understanding of the structural characteristics of the instrument.

The instrument comprises essentially a knurled or otherwise roughened handle 1 adapted to be grasped by the hand of the operator; a shaft 2 on which the handle is secured; a needle-carrying arm 3 secured to and projecting laterally from the shaft 2; a curved eye-pointed needle 4 secured to the arm 3, with the plane of the needle normal to the longitudinal axis of the shaft; and a shuttle mechanism, designated generally as S, supported from the shaft 2 and adapted to cooperate with the needle 4 in the formation of stitches. The needle, which has its center of curvature substantially coincident with the axis of the shaft, is secured to the free end of the arm 3 by means of a needle-clamp comprising an adjustable clamping jaw 5 adapted to engage one side of the shank of the needle to force the other side thereof into contact with the walls of a needle-receiving slot 6 formed in the free end of the arm 3. The jaw 5 carries a laterally projecting pin 7 which passes through a bore 3^a in the arm 3 into an aperture 3^b in which is located a needle-clamp actuating nut 8 threaded on the pin 7. Rotation of the nut 8 forces the jaw into and out of clamping contact with the

shank of the needle. A screw 9 threaded into the arm 3 has its head overlying the needle-receiving slot 6 and serves as a locating abutment for the shank 4^a of the needle. A suture-guiding channel 10 is formed in the clamp-jaw 5 to direct a suture-thread *n* from a source of supply to a groove formed in the outer convex portion of the blade of the needle and leading to the needle-eye 4^b in the pointed end thereof.

10 Fixed to the shaft 2 intermediate its ends, as by means of a collar 11^a secured by screws 11^b, is a spool-carrying arm 11 formed at its free end as a disk 11^c. Secured to the disk is a spool-holding casing 12 adapted to receive and hold a spool 13 carrying the needle suture *n*. The suture is wound on the spool 13 and extends outwardly through an aperture 12^a in the casing and thence to the upper end of the suture-guiding channel 10 in the needle-clamping jaw 5. Slidably mounted in an aperture 11^d formed centrally of the disk 11^c is a spool-supporting pin 14 having projecting from opposite sides thereof the opposite ends of a cross-pin 15 normally seated in notches 11^e formed in one face 11^f of the disk 11^c adjacent the aperture 11^d. The spool 13 is provided with a central bore 13^a adapted to fit upon one end of the pin 14 with the inner flange 16 of the spool in contact with the face 11^f of the disk 11^c and adjacent the cross-pin 15. A nut 17 (Fig. 11) threaded on one end 14^a of the pin 14, contacts with the outer flange 16^a of the spool 13 and prevents relative axial movement between the spool and the spool-pin 14. The opposite end of the pin 14 projects through the arm 11 and has threaded thereon a cup-nut 18 which receives one end of a compression spring 19 surrounding the pin 14 between the nut 18 and the disk 11^c. This spring normally urges the pin 14 axially in a direction to cause the cross-pin 15 to be moved out of contact with the spool 13 and seated in the notches 11^e and to force the flange 16 of the spool into contact with the adjacent face 11^f of the disk 11^c.

45 Provision is made for locking the spool against rotation except when it is desired to draw suture-thread therefrom. This provision comprises a stud 20 projecting from the face 11^f of the disk 11^c and a series of holes 13^b formed in the flange 16 of the spool 13. Under the influence of the compression spring 19, the flange 16 of the spool is forced into contact with the end of the stud 20 and therefore a slight rotation of the spool will cause one of the holes 13^b, which substantially correspond in size and location to the stud, 50 to be aligned with the stud which thereupon will enter the hole and lock the spool against further rotation.

When it is desired to permit rotation of the spool, so that suture-thread may be drawn therefrom, the operator will push downwardly on the nut 18. This will cause the pin 14 to be moved axially, in opposition to the compression spring 19, whereupon the cross-pin 15 will contact and shift the spool axially and cause the hole 13^b 55 to be disengaged from the stud 20 thereby unlocking the spool and permitting it to be rotated. When pressure on the nut 18 is relieved the spool will again be moved into contact with the stud and the stud 20 will re-engage one of the holes 13^b as above described.

70 The shuttle mechanism, which cooperates with the needle in the formation of stitches, comprises a shuttle-holder 21 having a trough-like portion 22 carrying a shuttle 23 therein. The shuttle-holder is supported on the shaft 2 for

rectilinear and rotative movement. The shuttle-holder includes a sleeve 25 slidably mounted on the shaft 2 and having a laterally projecting bifurcated arm 26 terminating in a split sleeve 27 which embraces a core element 21^a to which the portion 22 is secured as by a set-screw 21^b (see Fig. 16). A pinch screw 28 connecting the two portions of the split arm 26 causes the sleeve 27 frictionally to grip the core element 21^a. A pin 29 projecting laterally from the core element fits between the opposed walls of the split sleeve 27 and positively prevents rotation of the element in the sleeve.

The shuttle 23 is of the straight type and has a pointed end 23^a adapted to be projected into a loop of suture-thread thrown out by the needle 4. The shuttle is formed with a central bore into which is inserted a bobbin 30 carrying a second suture-thread *s* which, when the shuttle 23 and bobbin 30 are projected through the loop of needle-suture thread *n*, cooperates therewith in the formation of lock-stitches. To permit the shuttle, and the bobbin carried thereby, to pass completely through the loop of needle-suture, the shuttle is retained in the trough-like portion 22 of the shuttle-holder by a latch 31 pivotally mounted on a pin 32 carried by spaced ears 22^b which project laterally from the trough-like portion 22. The latch 31 has at its free end, an offset portion 31^a which loosely fits within a notch 23^b formed in the outer surface of the shuttle. There is sufficient clearance between the walls of the notch and the portion 31^a of the shuttle-retaining latch 31 to permit the needle-suture to pass therebetween. The latch 31 is normally maintained in its shuttle-holding position by means of a locking screw 33 threaded through one of the ears 22^b and having a reduced and unthreaded end 33^a adapted to enter an aperture 31^b in the latch 31. (See Figs. 15 and 18). When it is desired to remove the shuttle from the shuttle-holder, the screw 33 may be unscrewed to withdraw the end 33^a from the aperture 31^b, and the latch 31 may be swung outwardly about its pivot as shown in Fig. 18.

For a reason hereinafter to be explained, it is desirable that, during the operation of the instrument, the bobbin 30 normally be held against rotation so that suture-thread may not be pulled therefrom. This has been attained by forming, in the rear end of the bobbin, a transverse slot 30^a (similar to a screw-driver slot) and extending therewith the forward flat and rounded end 34^a (see Figs. 16 and 17) of a translatable but non-rotatable plunger 34 slidably mounted in a bore 21^c in the core element 21^a. At its rearward end the plunger 34 is pivotally connected, at 34^b, to a lever 35, fulcrumed at 36 between spaced ears 37 projecting from the core element 21^a. A flat spring 38, secured to an extension of the core element by screws 39 has its free end 38^a in pressure contact with the outer rounded surface 35^a of the lever 35 and thereby tends to swing the lever counterclockwise as viewed in Figs. 15 and 16, thereby forcing the plunger 34 inwardly and holding the forward end 34^a thereof in the slot 30^a in the bobbin. Contact of the upper portion of the lever 35 with the rear end of the core element 21^a, as shown at *x* in Fig. 16, limits the inward movement of the plunger 34. Sufficient clearance is provided between the end 34^a of the plunger 34 and the walls of the slot 30^a in the bobbin to permit the needle suture loop to pass therebetween as the shuttle is projected through that loop.

At certain times it is desirable to withdraw the plunger 34 to release the bobbin so that a length of suture-thread may be pulled therefrom. To effect such withdrawal of the plunger, the lever 35 has secured thereto a thumb-button 40 by which the lever may be turned about its fulcrum in opposition to the spring 38.

As hereinbefore stated, the shuttle mechanism is adapted to be rotated about the axis of the shaft 2 and also to be moved lengthwise thereof. To facilitate these movements the sleeve 25 has secured thereto by screws 41^a, a thumb-piece 41 having a rear face 41^b, a side face 41^c and a front face 41^d, all later to be referred to.

During a portion of the operation of the instrument, that is while the needle is being passed through the flesh at opposite sides of the wound, the entire shuttle mechanism is maintained in an elevated out-of-the-way position relative to the needle to give a better view of the wound and better access thereto. This position of the shuttle mechanism is shown in Figs. 1 and 2 and in full lines in Fig. 8. Detent means is provided for yieldingly holding the shuttle mechanism in its out-of-the-way position. As shown most clearly in Fig. 10 this detent means comprises a plunger 42 having a portion 42^a slidably fitted within a transverse bore 42^b in the shaft 2 and another portion 42^c projecting therefrom and extending through an aperture 42^d in the sleeve 11^a of the spool-carrying arm 11. A coil-spring 43 fitted within the bore 42^b, between the plunger 42 and a stop-screw 44, normally forces the plunger outwardly to cause the rounded outer end thereof to enter the lower end of a bore 45^a formed in a bushing 45 fitted within the thumb-piece 41, thereby to prevent relative rotation between the thumb-piece (and the parts connected therewith) and the shaft 2. An annular head 45^b formed on the bushing 45 engages the rounded end 42^c of the plunger 42 and serves to depress the plunger prior to the entrance of the end 42^c into the bore 45^a.

After the needle 4 has been passed through the flesh the shuttle mechanism is swung downwardly into operative position relative to the needle as shown in Fig. 3. This is effected by releasing the detent 42 from the thumb-piece 41 and thereafter rotating the thumb-piece, and the shuttle mechanism connected therewith, about the axis of the shaft 2. To effect release of the plunger 42 the thumb-piece 41 has slidably fitted therein, in line with the plunger 42, a push-pin 46 which normally rests upon the rounded outer end of the plunger. A transverse pin 47, secured in the thumb-piece and passing through the bushing 45 and a notch 46^a formed in the side of the push-pin, holds the push-pin in place and permits endwise movement thereof. At its outer end the push-pin has secured thereto a thumb-button 48 by means of which the pin may be depressed to release the detent.

To the end that the shuttle mechanism will be given the proper movements rotatively about the shaft 2 and lengthwise thereof to cause the shuttle properly to cooperate with the needle to form stitches, these movements of the shuttle mechanism are controlled by a continuous cam-groove 49 formed in the outer periphery of the shaft (see Figs. 6, 7 and 9) and a cooperating follower 50, carried by the thumb-piece 41, which tracks the cam-groove. This follower preferably is formed as the lower reduced end of a spring 75 plunger 51 slidably fitted within a thimble 52

secured within the thumb-piece 41. A coil-spring 53, surrounding the reduced upper end of the plunger 51 and interposed between a shoulder 51^a on the plunger and the closed upper end of the thimble, serves to urge the follower 59 against the bottom of the groove 49, thereby to produce a slightly frictional resistance between the shaft and the shuttle mechanism mounted thereon. This slight frictional resistance enables the operator to have better control of the shuttle mechanism during the operation of the instrument.

The shuttle-directing cam-groove 49 consists of a plurality of portions each of which guides or controls the movement of the shuttle mechanism during a portion of its entire stitch-forming cycle. Beginning with a portion 49^a (see Fig. 7), in which the follower 59 is located prior to the beginning of a sewing cycle, the cam-groove comprises a circumferential portion 49^b, a first forwardly extending straight portion 49^c, a first helical portion 49^d, a second straight portion 49^e, a first rearwardly extending straight portion 49^f, a second helical portion 49^g and a final rearwardly extending straight portion 49^h which terminates in the stop portion 49^a. As the follower 59 approaches the portion 49^a the projecting head portion 45^b of the bushing 45, carried by the thumb-piece 41, depresses the plunger 42 which thereafter snaps into the bore 45 and yieldingly retains the shuttle mechanism in its retracted position.

Operation

The operation of the instrument, above described, when suturing wounds by the seam shown in Fig. 20 is illustrated by Figs. 1 to 5, inclusive, and is as follows:

With the spool 13 and bobbin 30 wound with suitable suture-threads *n* and *s*, respectively, with the thread *n* threaded through the thread-guide 40 and thence through the needle-eye and with the free ends of the two threads tied together as shown at *t* in Figs. 1, 2, 5 and 20 the operator makes an initial stitch *i* beyond and across one end of the wound, designated as *w*. This is effected by inserting the needle through the flesh at opposite sides of the wound, projecting the shuttle through a thread-loop cast out by the needle, retracting the shuttle, withdrawing the needle and thereafter tightening the stitch by bodily moving the instrument away from the wound, all as will hereinafter be described in detail. Thereafter by making a succession of stitches along the wound, each spaced from the last stitch, a continuous lock-stitch seam will be made drawing the flesh, at the opposite sides of the wound, together into abutting relation as indicated at *v* in Figs. 1, 2 and 22.

Each stitch is made in the following manner: The operator, grasping the handle of the instrument as illustrated in dotted lines in Fig. 1, with the thumb against the side of the thumb-piece 41, places the point of the needle on the flesh adjacent one side of the wound. Then by turning the hand and rotating the instrument forwardly substantially on its longitudinal axis, (pressure being applied against the side of the thumb-piece) the point of the needle is caused to pass into and out of the flesh at opposite sides of the wound, as indicated in Fig. 2. It will be noted that during this portion of the operation the shuttle mechanism is retracted and rotated to an out-of-the-way position where it does not obstruct the view of the wound or interfere with the manipulation of the needle.

Having passed the needle through the flesh as shown in Fig. 2 the operator next depresses the thumb button 48, thereby releasing the detent 42^a, 45, and rotates the shuttle mechanism downwardly about the axis of the shaft, the follower 59 passing through the portion 49^b of the shuttle-controlling cam-groove 49. This rotation of the shuttle mechanism, together with a slight backward rotation of the entire instrument on its longitudinal axis places the pointed end 23^a of the shuttle 23 in alignment with, but slightly behind, the thread-loop *l* thrown out by the needle 4. Next the operator places his thumb against the rear face 41^b of the thumb-piece 41, (as shown in Fig. 3) and pushes forwardly thereon. This moves the shuttle mechanism forwardly on the shaft 2 and projects the pointed end of the shuttle into the thread-loop *l* (as shown in Fig. 3). Continued forward movement of the shuttle mechanism, under the influence of the operator's thumb, while the follower 59 tracks the straight portion 49^c of the shuttle-controlling cam-groove 49, projects the shuttle and the bobbin therein, almost completely through the needle thread loop *l*. Still further forward movement of the shuttle mechanism to the position shown in Fig. 4 completes the projection of the shuttle and bobbin through the loop *l* and, as the follower 59 tracks the helical portion 49^d of the cam-groove, the shuttle mechanism is given a combined endwise and sidewise movement thereby drawing the thread-loop *l* off the rear end of the shuttle and laterally between the bobbin 30 and its rotation restrainer 34, whereupon the thread-loop is held by the shuttle retainer latch 31. Next the operator places his thumb on the front face 41^c of the thumb-piece 41, (as shown in Fig. 5) and draws rearwardly thereon. This retracts the shuttle mechanism to its initial position, the follower passing successively through the straight portion 49^e, the helical portion 49^f and the straight portion 49^h of the shuttle-controlling cam-groove 49 until it reaches its stop position 49^a. The thread-loop *l* is then temporarily and frictionally retained between the offset portion 31^a of the shuttle-retainer 31 and the side of the shuttle 23, as shown in Fig. 5. Finally the instrument is rotated reversely to withdraw the needle from the flesh and moved bodily away from the wound to withdraw the loop *l* from the shuttle-retainer and to tighten the stitch. Tightening of the stitch, by bodily movement of the instrument, is possible because of the fact that both the spool 13 and the bobbin 30 are then locked against rotation and therefore no thread may be pulled therefrom.

As hereinbefore stated, this invention also contemplates suturing wounds by a method which includes additionally interlocking the two suture-threads at the outer face of the wound to give added strength to the seam and better to hold the opposite marginal portions of the wound aligned and in contact with each other. This method of suturing is illustrated in Fig. 21 in which the needle-suture *n* and the shuttle-suture *s* are locked together below the outer surface of the wound as indicated at *y* and additionally interlocked above said surface as indicated at *z*. It will readily be perceived that with this method of suturing, the overlying threads will cooperate with the lower locked threads *y* to hold the flesh, at opposite sides of the wound, in abutting contact and will hold the marginal portions thereof in alignment with each other.

This method may be performed by use of the

instrument hereinbefore described by rotating the instrument between successive stitches thereby to interlock the needle and shuttle-sutures above the outer face of the wound. When producing this form of suture, the instrument is moved away from the wound after each stitch has been formed, thereby to tighten the stitch. Then, with the instrument held substantially in the position shown in Fig. 23 and with the needle and shuttle-sutures running directly from the last stitch to the needle and shuttle, respectively, as shown in full lines in that figure, the user rotates the instrument substantially on its longitudinal axis in the direction indicated by the arrow *a* to the position shown in Fig. 24. Thus it will be seen that the positions of the needle and the shuttle are reversed with respect to the last stitch formed and the two suture-threads are thereby crossed as indicated at *b* in Fig. 24. Further rotation of the instrument in the direction of the arrow *a* to effect one complete turn thereof, will cause the instrument to re-assume the position shown in Fig. 23 and cause the two suture-threads to be interlocked above the wound as indicated in dotted lines at *c* in Fig. 23. Except for this rotation of the instrument between successive stitches the method of operating the instrument is the same as above described.

This invention also contemplates the tying-off of the seam, at the finishing end thereof, to prevent loosening of the stitches or ravelling of the seam. This is effected, as shown in Figs. 20, 21 and 22, by turning the instrument on its longitudinal axis to interlock the threads above the wound, as hereinbefore described, and thereafter making through either the needle puncture of the last stitch *s^x* of the seam or closely adjacent thereto, a tying stitch *p* thus interlocking the threads both above and below the surface of the wound and finally severing the ends *n'* and *s'* of the needle and shuttle-sutures, respectively, at a substantial distance from the wound. Thereafter, the pulling of either thread end will merely result in the pulling of the interlocked loops beneath the surface of the wound to the opposite sides of the needle puncture without drawing the end of either thread through the needle puncture. In Figs. 21 and 22 the needle and shuttle-sutures are shown in full lines as severed a substantially equal distance from the tying stitch *p*. Now if the end of the needle-thread *n* be pulled outwardly as indicated in dotted lines in Fig. 22 the loop *s'''* of shuttle-thread will be pulled completely through the flesh to the position shown in said Fig. 22 but the end *s''* thereof will still project from the opposite side of the needle puncture of the tying stitch. Further pulling on the needle-suture *n* will not further affect the loop *s'''* as the strain is then transmitted directly to the interlocked thread-loops above the wound and thence to the final stitch *s^x* of the seam. Pulling on the shuttle-thread will result in a similar action only in the opposite direction as shown in dotted lines in Fig. 22.

While it may be desirable to have the two suture-threads locked together beneath the surface of the wound, as shown in Figs. 20 and 21, this is not essential. If desired, the so-called "ladder" stitch of Fig. 19 may be produced by pulling unevenly on the two threads when tightening the stitch. If greater tightening action is exerted on the shuttle-thread *s* that thread will lie straight along the surface of the flesh

5 at one side of the wound and the needle-thread *n* will extend through the flesh and interlock with the shuttle-thread at one side of the wound as shown in Fig. 19. It will readily be understood that if greater tightening action is exerted on the needle-thread than on the shuttle-thread, the result will be reversed, and the needle-thread will lie straight along the surface of the flesh and the shuttle-thread will extend through the flesh and interlock with the needle-thread at the opposite side of the wound.

10 Figs. 19 and 20^a illustrate another form of tying stitch for tying-off the suturing seam to prevent ravelling thereof. As disclosed in those figures a tying stitch *p* is made either through the needle puncture of the last suturing stitch or closely adjacent thereto in a manner similar to the making of the last stitch and without interlocking the suture-threads above the wound disclosed in Figs. 20 and 21. The sutures are then severed a substantial distance from the wound. With this form of tying stitch, if the end of the needle-thread is pulled until the thread extends substantially straight out from the last suturing stitch *s^x* of the seam, as indicated in Fig. 20^a, the loop *s'''* of the shuttle-thread will be pulled completely through the flesh to the position shown in said figure but the end *s''* of the shuttle-thread will still project from the opposite side of the needle puncture of the tying stitch. Further pulling on the needle-suture *n* will not further affect the loop *s'''* as the strain is then transmitted directly to the interlocked thread-loop of the final stitch *s^x* of the seam which cannot pull out because of the resistance offered by the tying stitch. Pulling on the shuttle-thread will result in a similar action only in the opposite direction.

15 In Fig. 25 there is disclosed a modified and simplified form of surgical stitching instrument adapted particularly for suturing wounds with the stitches and seams illustrated in Figs. 26, 27 and 28. This instrument differs from the one hereinbefore described in that it is devoid of the shuttle mechanism and therefore is not adapted to make lock stitches. Like the instrument hereinbefore described, this device includes a handle 1, shaft 2, needle-carrying arm 3, curved eye-pointed needle 4, needle-clamping jaw 5, spool-carrying arm 11 secured to the shaft 2, spool-holding casing 12 carried by the arm 11, needle-suture spool (not shown) in the casing 12 and means similar to that disclosed in Figs. 11 and 12 for holding the spool against rotation except when pressure is applied to the cup-nut 13. The only difference between the elements disclosed in this figure and the corresponding elements disclosed in Figs. 1 to 6 and Figs. 11, 12 and 13 is that in the modified construction the shaft 2 does not contain any shuttle-controlling cam-groove corresponding to the groove 49.

20 The suturing operation illustrated in Fig. 26, may readily be performed with the instrument shown in Fig. 25 by grasping the instrument by the handle, rotating it on its longitudinal axis in one direction thereby passing the pointed end of the needle 4 into and out of the flesh at the opposite sides of the wound, seizing the free end of the suture-thread *n*, rotating the instrument in the opposite direction to withdraw the needle from the flesh, severing the suture-thread between the flesh and the needle and finally tying together the two ends of the suture-thread projecting from the flesh at opposite sides of

the wound. This operation products an individual stitch as shown at *f* in Fig. 26.

The suturing seam shown in Fig. 27 may be made by the instrument shown in Fig. 25 by repeatedly passing the pointed end of the needle through the flesh as above described, slightly retracting the needle to cause it to throw out a thread-loop *l''*, grasping that loop and carrying it forward, fully retracting the needle and again passing its pointed end through the flesh at opposite sides of the wound and through the previously formed loop *l''*, thus forming a conventional chain-stitch seam.

In Fig. 28 there is disclosed a suturing seam utilizing an "overedge" or "overcast" chain-stitch. This seam also may be made by the instrument shown in Fig. 25 by operating it as described in connection with the seam shown in Fig. 27 except that the thread-loop *l''* is carried diagonally across the wound *w* and the needle, in entering the flesh in making the next succeeding stitch, passes into and through said loop.

From the foregoing it will be perceived that I have provided a new and improved method of suturing wounds and have also provided a simple and practical hand-carried and hand-manipulated instrument by means of which that method may be practiced.

Having thus set forth the nature of the invention, what I claim herein is:—

1. A surgical stitching instrument, comprising a handle, a shaft projecting from said handle, a curved eye-pointed needle mounted on said shaft with the plane of the needle transverse to the longitudinal axis of the shaft, a support carried by said instrument and projecting to one side thereof, a suture-supply spool mounted on said support with its axis off-set from the longitudinal axis of the instrument, means including interengaging elements provided by said support and said spool, respectively, for preventing rotation of the spool, and means for bodily shifting said spool to disengage it from the rotation-preventing element provided by said support.

2. A surgical stitching instrument as set forth in claim 1 in which the support for the suture-supply spool carries an endwise shiftable spool-supporting pin and a stationary spool-engaging stud; in which a flange of the spool is formed with apertures adapted to receive said stud; in which spring means acts to shift the spool into engagement with said stud to lock the spool against rotation; and in which manually actuatable means is provided for shifting said pin and spool axially to disengage the spool from said stud.

3. A surgical stitching instrument as set forth in claim 1 in which the support for the suture-supply spool carries a stationary spool-retaining element; in which the spool is provided with a portion adapted to engage said element to prevent rotation of the spool; in which a spring normally urges said spool and element into locking engagement; and in which manually actuatable means is provided for shifting said spool axially to disengage it from said element.

4. A surgical stitching instrument comprising a handle, a shaft projecting from and aligned with said handle, a curved eye-pointed needle mounted on said shaft with the plane of the needle transverse to the longitudinal axis of said shaft and with the center of curvature of the needle substantially coincident with the axis of said shaft and handle.

5. A surgical stitching instrument comprising a handle, a shaft projecting axially from said handle, an arm projecting laterally from the end of said shaft remote from said handle, a needle-clamp at the free end of said arm, and a curved eye-pointed needle mounted in said needle-clamp.

6. A surgical stitching instrument comprising a handle, a shaft projecting axially from said handle, an arm projecting laterally from the end of said shaft remote from said handle, a spool-holder supported by said instrument adjacent the juncture of said shaft and handle and a needle-clamp at the free end of said arm.

7. A surgical stitching instrument comprising a handle, a shaft projecting from said handle, an arm projecting laterally from the end of said shaft remote from said handle, a curved eye-pointed needle removably secured to said arm, a suture supply spool mounted on said instrument between said handle and needle-clamp, and manually releasable means to lock said spool against rotation.

8. In a hand-carried and hand-manipulated surgical stitching instrument having a handle and a shaft projecting from said handle, the combination with a curved eye-pointed needle carried by said shaft, of a shuttle having a rectilinear loop-taking movement relative to said needle and lengthwise of said shaft.

9. In a hand-carried and hand-manipulated surgical stitching instrument having a needle-supporting shaft, the combination with a curved eye-pointed needle carried by said shaft, of a straight shuttle having a rectilinear loop-taking movement relative to said needle and lengthwise of said shaft and a movement sidewise of itself after it has been projected well into the needle-thread loop, and manually actuatable means for giving said movements to said shuttle.

10. A hand-operated surgical stitching instrument comprising suture-carrying eye-pointed needle and complemental shuttle elements, and a shaft carrying said elements, one of said elements being fixedly and the other movably related to said shaft, and manually actuatable means for moving the movable element relative to said shaft and fixed element.

11. A hand-operated surgical stitching instrument having, in combination, an eye-pointed needle carrying a suturing thread, a needle-holder, a loop-taker complemental to said needle and adapted to take thread loops therefrom in the formation of stitches, said loop-taker being movably supported by said needle-holder, means on said needle-holder to retain said loop-taker in an out-of-the-way position removed from said needle, and means to move said loop-taker from said out-of-the-way position into loop-taking position relative to said needle.

12. A hand-operated surgical stitching instrument comprising a thread-carrying eye-pointed needle-element, a loop-taker element complemental to said needle-element and adapted to take thread loops therefrom in the formation of stitches, and a shaft carrying said elements, said needle-element being fixedly related to said shaft and said loop-taker element being movably related to said shaft, and manually actuatable means for moving said loop-taker element.

13. A hand-carried and hand-manipulated surgical stitching instrument having, in combination, complemental needle and shuttle elements, a shaft supporting said elements, means to move said shuttle element in a predetermined

path on said shaft to cause it to take thread-loops from said needle, a bobbin carried by said shuttle and adapted to be passed through said thread-loops to form lock-stitches, and a supporting handle connected to said shaft.

14. A surgical stitching instrument having, in combination, a curved eye-pointed needle adapted to carry a suture-thread, a shaft carrying said needle, a handle on said shaft remote from said needle, a shuttle-holder movable on said shaft between said handle and needle, and a suture-carrying shuttle in said shuttle-holder.

15. A surgical stitching instrument comprising a handle, a shaft projecting from said handle, a curved eye-pointed needle mounted at the free end of said shaft with the plane of the needle transverse to the longitudinal axis of said shaft, a shuttle, and a shuttle-holder slidable on and lengthwise of said shaft.

16. A surgical stitching instrument comprising a handle, a shaft projecting from said handle, a curved eye-pointed needle mounted at the free end of said shaft with the plane of the needle transverse to the longitudinal axis of said shaft, a shuttle, and a shuttle-holder rotatable on and slidably lengthwise of said shaft.

17. A surgical stitching instrument comprising a handle, a shaft projecting from said handle, a curved eye-pointed needle mounted at the free end of said shaft with the plane of the needle transverse to the longitudinal axis of said shaft, a sleeve slidable on said shaft, a shuttle, and a shuttle-holder laterally offset from and fixed to said sleeve.

18. A surgical stitching instrument comprising a handle, a shaft projecting from said handle, a curved eye-pointed needle mounted at the free end of said shaft with the plane of the needle transverse to the longitudinal axis of said shaft, a sleeve slidable on said shaft, a shuttle, a shuttle-holder laterally offset from and fixed to said sleeve, a suture bobbin in said shuttle, and manually releasable means on said shuttle-holder to lock said bobbin against rotation in said shuttle.

19. A surgical stitching instrument having, in combination, a curved thread-carrying needle, a shaft carrying said needle, a handle for said shaft, a thread-carrying shuttle movable relative to said shaft, and manually releasable devices to lock the needle and shuttle suture-threads against endwise movement relative to said instrument.

20. A surgical stitching instrument having, in combination, a curved eye-pointed needle, a shaft carrying said needle, a handle for said shaft, a needle-suture-supply spool, a holder therefor, a shuttle movable relative to said shaft, a suture-carrying bobbin held by said shuttle, and manually releasable means to lock said spool and bobbin against rotation in their respective holders.

21. In a surgical stitching instrument, a shuttle comprising a hollow cylindrical body having a loop-taking point at one end and an opening at its opposite end, a suture bobbin in said shuttle, a shuttle-carrier, and manually releasable means on said shuttle-carrier extending through the open end of said shuttle into locking engagement with said suture bobbin to prevent rotation of said bobbin within said shuttle at all times except when released by the operator.

22. A surgical stitching instrument having a handle, a shaft projecting from said handle, a curved eye-pointed needle carried by said shaft with its plane transverse to the longitudinal axis of said shaft, a shuttle, a shuttle-carrier offset

from the longitudinal axis of said shaft and mounted to slide lengthwise of and turn about said axis, and cam-and-follower devices on said shaft and shuttle-carrier to control the rotative position of said shuttle-carrier on said shaft in the motion of the shuttle-carrier longitudinally of said shaft.

23. A surgical stitching instrument having a handle, a shaft projecting from said handle, a curved eye-pointed needle carried by said shaft with its plane transverse to the longitudinal axis of said shaft, a shuttle, a shuttle-holder offset from the longitudinal axis of said shaft and mounted to slide lengthwise of and turn about said axis, cam-and-follower devices on said shaft and shuttle-holder to control the rotative position of said shuttle-holder on said shaft in the motion of the shuttle-holder longitudinally of said shaft, and manually releasable means to lock said shuttle-holder to said shaft in a retracted position.

24. In a hand-carried and hand-manipulated surgical stitching instrument, the combination with a curved eye-pointed needle and a handle on which said needle is mounted with the plane of the needle transverse to the longitudinal axis of said handle, of a straight shuttle, and manually operated means to project said shuttle lengthwise of itself and said handle and transversely of the plane of the needle into a suture-loop presented at the concave side of said needle.

25. A surgical stitching instrument having, in combination, a curved needle formed with a suture-carrying eye adjacent the point thereof, a shaft carrying said needle and having its longitudinal axis substantially normal to the plane of said needle, a suture-carrying shuttle, a shuttle-holder slidable lengthwise of and turnable about the axis of said shaft, and means to first turn said shuttle-holder about the shaft axis from an out-of-the-way position into loop-taking position and thereafter to slide the shuttle-holder lengthwise of the shaft axis to project the shuttle into a suture-loop presented by said needle.

26. A hand-carried and hand-manipulated surgical stitching instrument having, in combination, a curved eye-pointed needle, a shuttle, a shuttle-holder, means including a shaft to support said shuttle-holder in an out-of-the-way position relative to said needle, and means including an element slidable and rotatable on said shaft to shift said shuttle-holder first in one direction into position for cooperation of said shuttle with said needle and then in a different direction to project the shuttle into a thread-loop presented by said needle.

27. A surgical stitching instrument comprising a handle, a shaft projecting from said handle, a curved eye-pointed needle mounted on said shaft with the plane of the needle normal to the longitudinal axis of said shaft, a shuttle-holder movable lengthwise of said shaft, a shuttle carried by said shuttle-holder and cooperating with said needle in the formation of stitches and a thumb-piece projecting from said shuttle-holder radially of the axis of said handle and cooperating with the handle to facilitate manual rotation of said instrument substantially on its longitudinal axis, and to actuate said shuttle-holder.

28. A surgical stitching instrument having, in combination, a curved needle formed with a suture-carrying eye adjacent the point thereof, a shaft carrying said needle and having its lon-

gitudinal axis substantially normal to the plane of said needle, a handle on said shaft, a suture-carrying shuttle, a shuttle-holder slidably lengthwise of and turnable about the axis of said shaft, a continuous shuttle-holder-directing cam-groove formed in the periphery of said shaft and a stud on said shuttle-holder engaging said cam-groove, said cam-groove having a first portion extending circumferentially thereabout, a second portion extending lengthwise of the shaft, a third portion extending substantially helically around the shaft, said second and third portions extending forwardly away from said handle and serving to direct the shuttle-holder in its forward movement, a fourth portion extending lengthwise of the shaft, a fifth portion extending helically around the shaft in a direction opposite to the first named helical portion and a sixth portion extending lengthwise of the shaft and connecting with said first portion, said fourth, fifth and sixth portions of the cam-groove serving to direct said shuttle-holder in its retracting movement.

29. A surgical stitching instrument having, in combination, a shaft, a curved eye-pointed needle mounted thereon, a shuttle, a shuttle-holder slidably mounted on said shaft, means to support said shuttle-holder in an out-of-the-way position relative to said needle, means to shift said shuttle-holder on said shaft first in one direction into position for cooperation with said needle, then in a different direction to project the shuttle through a thread-loop presented by said needle and finally to retract it to said out-of-the-way position, and a manually controlled detent to lock said shuttle-holder in said out-of-the-way position.

30. A surgical stitching instrument comprising a handle, a shaft projecting from said handle, a curved eye-pointed needle mounted at the free end of said shaft with the plane of the needle transverse to the longitudinal axis of said shaft, a sleeve slidable on said shaft, an arm projecting radially from said sleeve, a shuttle-holder carried by said arm, and having a trough-like shuttle receiving portion, a shuttle located in said trough-like portion and having its pointed end projecting from the open end thereof, and a shuttle retainer secured to said shuttle-holder and overlying said trough-like portion to maintain said shuttle therein.

31. A surgical stitching instrument comprising a handle, a shaft projecting from said handle, a curved eye-pointed needle mounted at the free end of said shaft with the plane of the needle transverse to the longitudinal axis of said shaft, a sleeve slidable on said shaft, an arm projecting radially from said sleeve, a shuttle-holder carried by said arm, and having a trough-like shuttle receiving portion, a shuttle located in said trough-like portion and having its pointed end projecting from the open end thereof, a shuttle-retaining element pivotally mounted on said shuttle-holder and swingable into position to maintain said shuttle in its holder, and means to secure said element in shuttle-holding position.

32. In a surgical stitching instrument, a shuttle comprising a hollow cylindrical body having a loop-taking point at one end and an opening at its opposite end, a suture bobbin in said shuttle and having an aperture in one end thereof, a shuttle-holder, a non-rotatable spring-pressed plunger carried by said shuttle-holder with its axis substantially in line with the axis of said

bobbin, the forward end of said plunger being adapted to engage the aperture in said bobbin to prevent rotation thereof, and manually actuatable means to withdraw the forward end of said plunger from the aperture in the bobbin to permit rotation of the bobbin in the shuttle.

33. In a surgical stitching instrument, a shuttle comprising a hollow cylindrical body having a loop-taking point at one end and an opening 10 at its opposite end, a suture bobbin in said shuttle and having a transverse slot in one end thereof, a shuttle-holder, a non-rotatable spring-pressed plunger carried by said shuttle-holder with its axis substantially in line with the axis of said bobbin, the forward end of said plunger being flattened and adapted to fit into the slot in said bobbin to prevent rotation thereof, and a manually actuatable lever fulcrumed on said shuttle-holder and engaging said plunger 15 to withdraw the forward end of the plunger from the slot in the bobbin to permit rotation of the bobbin.

34. A surgical stitching instrument having, in combination, a curved eye-pointed needle, a shaft carrying said needle, a handle for said 25 shaft, a shiftable needle-suture-supply spool, a holder therefor comprising a fixed casing, interengaging means provided by said spool and casing to prevent rotation of said spool in said casing, and manually operable means for bodily 30 shifting said spool thereby to render said interengaging means ineffective to hold said spool against rotation.

35. A surgical stitching instrument having, in combination, a curved eye-pointed needle, a shaft carrying said needle, a handle for said shaft, a needle-suture-supply spool, a holder therefor comprising a cup-like casing secured to said shaft and adapted to receive said spool, a 40 spring-pressed plunger mounted coaxially in said casing and extending through said spool, a nut threaded on said plunger to retain said spool thereon, interengaging elements on said spool and casing adapted to prevent rotation of 45 the spool in the casing, an abutment carried by said plunger adapted to engage said bobbin, and manually actuatable means to shift said plunger and the abutment carried thereby axially thereby to disconnect said interengaging means 50 thereby to permit rotation of said spool.

36. A surgical stitching instrument comprising a handle, a shaft projecting from said handle, an arm projecting laterally from the end of said shaft remote from said handle, the forward free end of said arm being formed with a needle-receiving slot, a needle-clamping jaw slidably mounted on the free end of said arm and having a jaw portion cooperating with the walls of said slot to clamp the shank of a needle 60 therebetween, a threaded pin connected to said jaw and extending through an aperture formed lengthwise of said arm, and a manually rotatable nut, located in a transverse opening in said arm and spaced from the end thereof, threaded 65 on said pin for shifting said clamping jaw to effect clamping and unclamping of said needle.

37. A surgical stitching instrument comprising a handle, a shaft projecting from said handle, a curved thread-carrying eye-pointed needle mounted on said shaft with the plane of the needle transverse to the longitudinal axis of the shaft and with the center of curvature of the needle substantially coincident with the axis of the shaft, a shuttle, and a shuttle-holder supported on and slidably lengthwise of the shaft to

project said shuttle through a loop of thread carried by said needle and rotatable about the axis of said shaft to move said shuttle to an out-of-the-way position removed from said needle, said shuttle being arranged to rotate in an arc the radius of which is less than the radius of curvature of said needle.

38. A surgical stitching instrument comprising a handle, a shaft projecting from said handle, an arm projecting laterally from the end of

5 said shaft remote from said handle, a curved eye-pointed needle mounted on said arm with the plane of the needle transverse to the axis of said shaft, a second arm carried by said instrument and projecting radially therefrom, and a suture supply spool mounted on said second arm with its axis off-set from the longitudinal axis of the instrument.

JOHN D. KARLE.
